UNITED STATES PATENT OFFICE

91,968

DESIGN FOR A COMBINED CIGARETTE LIGHTER AND ASH TRAY

Henry T. Schiff, Chicago, Ill.

Application November 18, 1933, Serial No. 49,785

Term of patent 3½ years

To all whom it may concern:

Be it known that I, HENRY T. SCHIFF, a citizen of the United States, and resident of Chicago, in the county of Cook and State of Illinois, have invented a new, original, and ornamental Design for a Combined Cigarette Lighter and Ash Tray, of which the following is a specification, reference being had to the accompanying drawing, forming a part thereof.

bined cigarette lighter and ash tray showing my new design; and

Fig. 2 is a top plan view of the same.

I claim:

The ornamental design for a combined cigarette lighter and ash tray, substantially as shown.

Signed at Chicago, in the county of Cook, and State of Illinois, this 31st day of October, A. D. 1933.

HENRY T. SCHIFF.
